US00D768219S

(12) **United States Design Patent** (10) **Patent No.:** **US D768,219 S**
(45) **Date of Patent:** **** Oct. 4, 2016**

(54) **ROBOT SYSTEM FOR MEDICAL SURGERIES**

(71) Applicant: **Aktormed GmbH**, Barbing (DE)

(72) Inventors: **Peter Kraus**, Neualbenreuth (DE);
Robert Geiger, Metten (DE)

(**) Term: **14 Years**

(21) Appl. No.: **29/512,181**

(22) Filed: **Dec. 17, 2014**

(51) **LOC (10) Cl.** **15-99**

(52) **U.S. Cl.**

USPC **D15/199**; D24/185

(58) **Field of Classification Search**

USPC D15/199; D21/578-583, 621, 622;
D24/185

See application file for complete search history.

(57) **CLAIM**

The ornamental design for a robot system for medical surgeries, as shown and described.

DESCRIPTION

FIG. 1 is a perspective view of the robot system for medical surgeries;

FIG. 2 is a front view of the robot system for medical surgeries;

FIG. 3 is a rear view of the robot system for medical surgeries;

FIG. 4 is a right side view of the robot system for medical surgeries;

FIG. 5 is a left side view of the robot system for medical surgeries;

FIG. 6 is a top view of the robot system for medical surgeries; and,

FIG. 7 is a bottom view of the robot system for medical surgeries.

1 Claim, 6 Drawing Sheets

FIG. 1

FIG. 2

FIG. 3

FIG. 4

FIG. 5

FIG. 6

FIG. 7
